UNITED STATES PATENT OFFICE.

ALFRED W. BRUCE, OF NEW YORK, N. Y.

LATERAL-MOTION APPLIANCE FOR LOCOMOTIVE DRIVING BOXES.

1,414,455.

Specification of Letters Patent. Patented May 2, 1922.

Application filed August 18, 1921. Serial No. 493,299.

To all whom it may concern:

Be it known that I, ALFRED W. BRUCE, a citizen of the United States, and a resident of New York, in the county and State of New York, have invented a certain new and useful Improvement in Lateral-Motion Appliances for Locomotive Driving Boxes, of which improvement the following is a specification.

10 The object of my invention is to provide means for affording and controlling lateral motion in the driving boxes of locomotive engines, which shall be of simple, and inexpensive construction, and of ready applicability in locomotives of the various present standard types, with the result of enabling a locomotive, having a comparatively long rigid wheel base, to pass through curves of comparatively short radius, without 20 liability to derailment, and without inducing undue or excessive wear of wheel flanges and rails.

The improvement claimed is hereinafter fully set forth.

25 In the accompanying drawings: Figure 1 is a view, in elevation, of a locomotive frame pedestal, with an axle and driving box in vertical transverse section, illustrating an application of my invention; Fig. 2, 30 a vertical central section through the same; and Figs. 3 and 4, views, taken similarly to Figs. 1 and 2, respectively, illustrating a structural modification.

In the practice of my invention, referring 35 descriptively to the specific embodiment thereof which is herein exemplified, and first to Figs. 1 and 2, the driving boxes, 4, adjoining the driving wheels, 6, which are fixed on opposite ends of the driving axle, 8, are 40 provided with the usual journal bearings, 4^a, and oil cellars, 4^b, and are fitted in the pedestal jaws, 3, of the side frame members, which connect the upper and lower frame rails, 1 and 2, thereof, between wedges, 4^c, and shoes, 4^d, in the ordinary manner. The 45 open spaces between the sections of the lower frame rails, 2, are spanned by pedestal ties, 5, suitably connected to the lower frame rails.

50 The portion of the weight of the locomotive which is carried on the driving axle, 8, is transmitted to the driving boxes, 4, through springs, 9, which bear, centrally, on seats, 10^a, at the ends of a rigid yoke or 55 spring supporting beam, 10, extending transversely of the locomotive, and adapted

to move vertically, but not laterally, relatively to the side frame members. It will, of course, be understood that the springs are connected, by hangers at their ends, to the side frame members, either directly or through the intermediation of equalizers, in the ordinary manner. The springs supporting beam, 10, is guided, in its vertical movements, by guide lugs, 10^b, projecting downwardly from its body, and adapted to fit, with easy working clearance, against the upper frame rails, 1, or rubbing plates secured thereon.

The ends of the supporting beam, 10, are 70 supported upon the driving boxes, 4, through the intermediation of vibratable rockers, 11, which are of the three point suspension type, and are of inverted U section, their legs extending downwardly on opposite sides of the upper frame rails, 1, and fitting in recessed seats in the tops of the driving boxes, and their upper portions connecting their legs, constituting the bearings on which the supporting beam, 10, itself 80 rests, rollers, 12, being preferably, interposed between the rockers and the beam.

In the operation of a locomotive engine in which a construction embodying the essential features of that above described, or 85 their equivalents, is applied, when one of the driving wheels is laterally deflected, in either direction, from its normal position, relatively to the adjacent side frame, which deflection is effected by the resistance 90 opposed by the contact of the outer track rail with the flange of the adjacent driving wheel, upon the passage of the locomotive from a tangent to a curve of the track, the accompanying lateral movement of the driving box, swings the rocker, 11, in direction 95 similar to that of the movement of the box. This movement of the rocker, which acts to raise the supporting beam, 10, is resisted by the weight carried by the adjacent end thereof, this resistance acting, through the roller 12, and the bearing on the lower end of the outer leg of the rocker, and being determined by the angularity of a line connecting the axes of these bearings. The beam, 105 10, being prevented from moving laterally, the springs, 9, participate in its vertical movement, as the resistance stated is overcome, without disturbance of their relation, laterally, to the side frame members or 110 equalizer connections.

In the construction illustrated, the resist-

ance is exerted on one side of the locomotive only, the journal at the opposite end of the axle sliding through its driving box without instituting any resistance other than lateral journal friction, which, if the journal is properly lubricated, will be trifling. As the resistance of the rail decreases, in the passage of the locomotive from a curve to a tangent of the track, the superimposed weight on the rocker, forces the driving wheel out to its normal position, and the load is again carried on all three bearing points of the rocker, as indicated in Fig. 2.

The structural modification shown in Figs. 3 and 4, complies, in all essential particulars, with the construction above described, differing therefrom only in the substitution of another form of three point suspension rocker, 11^a, for the rocker, 11, of Figs. 1 and 2. The rocker is, in this instance, of upright U section, its legs extending upwardly on opposite sides of the upper frame rail, 1, and its lower portion, connecting the legs, being provided with a central segmental bearing, 11^b, extending in a longitudinal plane of the frame, and fitting in a corresponding groove or recess in the top of the driving box, 4. A bearing plate, 12^a, is interposed between the upper ends of the legs of the rocker, 11^a, and is connected thereto by bolts, 13, and nuts. Two segmental bearings, 12^b, 12^c, extending in longitudinal planes of the frame, are formed on the top of the bearing plate, 12^a, said bearings fitting in corresponding grooves or recesses on the lower side of the spring supporting beam, 10.

The operation of this specific form of my invention in entering and passing from a curve of the track, is similar, in all essential particulars, to that of the construction shown in Figs. 1 and 2, and first above described.

I claim as my invention and desire to secure by Letters Patent:

1. In a locomotive engine, the combination of a side frame; a driving box, fitted with the capacity of relative movement therein; a spring supporting beam, which is vertically movable relatively to the driving box; and vibratable means, interposed between the supporting beam and the driving box, for transmitting resistance from one to the

other of said members, in planes on the opposite sides of the frame.

2. In a locomotive engine, the combination of a side frame; a driving box, fitted, with the capacity of relative movement therein; a spring supporting beam, which is vertically movable relatively to the driving box; and a rocker, extending, on opposite sides of the frame, between the supporting beam and the driving box, and bearing at two points on one of said members, and at one point on the other member.

3. In a locomotive engine, the combination of a side frame; a driving box, fitted with the capacity of relative movement therein; a spring supporting beam, which is vertically movable relatively to the driving box; and a rocker, of U form, the legs of which extend, on opposite sides of the frame, between the supporting beam and the driving box, and which bears at two points on one of said members, and at one point on the other member.

4. In a locomotive engine, the combination of a side frame; a driving box, fitted, with the capacity of relative movements, therein; a spring supporting beam, which is vertically movable relatively to the driving box; a rocker, of U form, the legs of which extend, on opposite sides of the frame, between the supporting beam and the driving box, and bear on said driving box; and a central bearing on the rocker, through which resistance is transmitted from the driving box to the supporting beam and vice versa.

5. In a locomotive engine, the combination of a side frame; a driving box, fitted, with the capacity of relative movement therein; a spring supporting beam, which is vertically movable relatively to the driving box; a rocker, of U form, the legs of which extend, on opposite sides of the frame, between the supporting beam and the driving box, and bear on said driving box; and a roller, interposed between a central bearing on the rocker and a bearing on the supporting beam.

ALFRED W. BRUCE.
